(57) **CLAIM**

The ornamental design for a combination ceiling fan and light fixture, as shown and described.

DESCRIPTION

FIG. 1 is a perspective view from below of a combination ceiling fan and light fixture in accordance with my design. FIG. 2 is a bottom plan view of the combination ceiling fan and light fixture in accordance with my design.

FIG. 3 is a top plan view of the combination ceiling fan and light fixture in accordance with my design.

FIG. 4 is a side elevation view of the combination ceiling fan and light fixture in accordance with my design; and, FIG. 5 is a front elevation view of the combination ceiling fan and light fixture in accordance with my design.

The front and rear elevation views are mirror images of each other except for the positioning of the blades.

The right side and left side elevation views are mirror images of each other except of the positioning of the blades.

The broken lines showing environmental structure are for illustrative purposes and form no part of the claimed design.
